OIL BURNER CONTROL

William H. Hutchins and Henry C. Rohr, Rochester, N. Y., assignors to General Motors Corporation, Detroit, Mich., a corporation of Delaware

Application December 3, 1936, Serial No. 113,962

7 Claims. (Cl. 200—138)

This invention pertains to control mechanism for heating apparatus and more particularly to what is known as master controls for operating fluid fuel burners.

5 In utilizing electric motors for discharging fluid fuel into a combustion chamber for heating purposes it is necessary to provide therefor a certain apparatus controlled directly by the presence or absence of heat within the combustion chamber 10 or associated heat ducts which will control the discharge of fuel into the furnace.

There are several abnormal conditions which must be protected against in the usual operation of the fluid fuel burner such as instances in which 15 the burner does not ignite when initially started; where the flame for some reason or other is extinguished during normal operation before the room thermostat is satisfied, or where there is a momentary current failure and to immediately 20 start the burner again in operation might cause an explosion. Under any one of these conditions it is necessary to provide safety means to either stop the burner or prevent the same from operating for a certain period of time until it is safe 25 to again resume operation.

It is therefore the object of our invention to provide control mechanism to accomplish the desired safety features above outlined.

It is a further object of our invention to provide 30 a unitary assembly to be applied to a position directly heated by the burner for controlling purposes.

It is a still further object of our invention to provide a unitary master control applied to the 35 stack of the burner for controlling the supplying motor.

With these and other objects in view the embodiments of our invention reside in the following specification and claims and are illustrated in the 40 accompanying drawings, in which:

Figure 1 is a horizontal section through the control unit in its assembled position on the stack.

Figure 2 is a vertical elevation of the control 45 unit taken on line 2—2 of Figure 1.

Figure 3 is a detailed view of the mercury switch controlling the ignition showing it in a different position from that of Figure 2.

Figures 3a and 3b are detail views similar to 50 Figure 3 showing the cooperating parts in different positions of operation.

Figure 4 is a sectional view taken on line 4—4 of Figure 2 showing the relay.

Figure 5 is a sectional view taken on line 5—5 55 of Figure 2 showing the warp switch construction.

Figure 6 is a sectional view taken on line 6—6 of Figure 2 and showing the stack drive.

Figure 7 is a perspective view of the whole control, parts being broken away to show the whole.

Figure 8 is a diagrammatic wiring diagram illustrating the connection of the master control and the control circuit.

Our control unit consists primarily of a metallic frame 2 roughly U-shaped in cross section, 10 as best shown in Figure 7, comprising a flat plate section 4 and two upstanding end portions 6, said end portions supporting between them a panel 8 of insulating material upon which the majority of the parts of the control apparatus are 15 mounted. Between the panel 8 and the plate 4 is supported a plate 10 of heat insulating material, such as asbestos block, to prevent the heat from being transmitted from the combustion chamber or stack to the control apparatus. In the central portion of the plate 4 is provided an opening 12 through which a rod 14 projects, said rod being concentric within a cylinder 16 which is secured to the outside face of the plate 4, the outer end of the cylinder 16 being reduced in diameter at a point 18 and carrying within it a flanged disk 20 having a small opening 22 therein which supports the rod 14 at a spaced point. The rod has an enlarged section 24 adjacent the disk 20 to prevent abnormal axial movement of the 30 rod.

Concentric with the rod and around the same is mounted a helical bimetallic coil 26, one end of said coil being secured to the outer end of the rod at a point 28 by a suitable screw and the inner 35 end being secured under the head of screw 30 which also secures the flanged disk 20 to the internal diameter of the reduced portion of the member at 18. This portion of the apparatus is adapted to project through the wall of a stack 31, the bimetallic element thereby being within the stack and subject to stack temperatures and the whole unit being mounted upon the stack wall by a suitable flange 32. As the bimetallic member 26 is heated, it tends to coil and rotate 40 shaft 14 which accomplishes various control functions later to be explained.

The end 6 of the supporting plate 4 has a pressed-out portion 33 carrying a U-shaped member 34 which assists in the supporting function on the stack wall. The control mechanism per se consists primarily of four different members: a transformer 36, an electrically heated warp switch designated generally at 38, an ignition switch 40 and operating mechanism therefor, and a relay 50

42. These are all mounted on the insulated panel 8 as are also suitable terminal screws such as those designated at 44.

The transformer 36 may be of any conventional design for stepping down 110 volts of current to some lower suitable control value. The warp switch 38 is of a type in which a bimetallic element 46 is supported at its lower end in an insulated block 48 and supports at its upper end one end of a bell crank lever 50, the opposite end carrying contact 52 and the whole lever being pivoted around a point 54. The insulating block 48, which supports the bimetallic arm 46, is itself supported on the lower end of a bimetallic strip 58 which is parallel to the strip 46 and is supported so that its warping reaction, due to temperature changes, is opposite to that in the strip 46, the combination of the two correcting for ambient temperatures. The upper end of the bimetallic strip 58 is riveted to a bracket 59 supported on the main supporting bracket 64. The bimetallic element 58 is provided with heat from an electric heating coil 56 mounted thereon. It is thus obvious that when heat has been applied to the heating element for some time the bimetallic element will rotate as a whole counterclockwise, as shown in Figure 5, to move toward the left hand extremity and eventually project through the opening 82 in the arm 50 which causes the bell crank to rotate in a counterclockwise direction breaking the contact between contact 52 and contact 60 which is mounted on an arm 62 riveted to the lower end of the bimetallic element 46. These two contacts 60 and 52 are directly connected in the motor circuit.

This whole structure is supported on a bracket 64 which is held to the plate 8 by suitable bolts 66. After the warp switch has once moved out from under the bell crank arm 50 and cools, it will move back in a clockwise direction but cannot move back to its original position because the upper end is locked in opening 82. It is therefore necessary to provide some resetting means which in this case is in the form of a plunger 68 supported in the outer portion of the bracket 64 within a circular housing 70. Concentric with the plunger 68 is a helical spring 72 which presses against a circumferentially enlarged portion 74 on the plunger 68 and against the bracket 64 in the base of the housing 70 to keep the plunger in its retracted position away from the contact. The inner end of the plunger 68 has a stepped portion 76, the smaller extremity of which is adapted to be forced against the arm 62 and the step itself adapted to encounter the lower end of the arm 78 of the bell crank lever carrying contact 52. This distance on the step portion 76 is so constructed that the end will push contact 60 outwardly far enough so that contact 52 will not touch the same during the resetting operation but once the lever 50 is back in position over the top of the bimetallic member 46, contact 60 will be allowed to touch contact 52 as the plunger is retracted to its normally inoperative position.

On the pivot shaft 54 is also provided a coil spring 80 to bias the rotation of the bell crank in a counterclockwise direction and to assure a breakage of the contacts 52 and 60. The pivot 54 is supported on an angled bracket 84 and projects through an opening 86 in the supporting bracket 64. This bracket 84 may be moved with respect to the bracket 64 and is set in its adjusted position by a threaded shaft and nut 88 so that the length of time of operation of the warp

switch may be varied by varying the amount that the bell crank lever 50 projects over the top of the warp arm 46.

As before mentioned, the rod 14 is adapted to be rotated by the bimetallic coil 26 which is affected by stack temperatures provided by combustion within the burner. This rod 14 extends through the back wall of the master control and also through a cup-shaped disk 90 which is inserted in an opening in the insulated panel 8. On the forward face of the panel 8 is secured a multi-angular bracket 92 by suitable bolts 94, said multi-angular bracket providing two aligned openings for the end of the shaft 14, said end being of reduced diameter with respect to the rest of the rod.

Adjacent the cup member 90 and surrounding the smaller end of the rod 14 is a flanged cylindrical member 96 which is adapted to extend from the inner surface of the cup-shaped member 90 to a portion of the bracket 92 through which the outer end of the rod extends and upon which it is press-fitted. Mounted upon this cylindrical member 96 are a plurality of washers 98 between two of which extend a helical coil spring 100 and between the next adjacent pair are located two friction disk washers 102 having between them a rotatable arm 104. With this mounting it is evident that the helical spring 100 will tend to press the two friction disks 102 tightly against the opposite faces of the rotatable arm 104 and cause the same to rotate with the shaft under normal conditions but allow relative movement of the two.

The angled bracket 92 has a further extended portion 94' which is again bent back at right angles through which the extreme end of the shaft 14 projects and through which a cotter pin is applied to prevent the disengagement of the apparatus. Loosely mounted upon the rod 14 between the angled bracket 92 and the extreme end thereof 94' is a substantially U-shaped bracket 108 which carries thereon clips 110 holding a mercury contact switch 112. This movable bracket merely utilizes the end of the rod as a pivot point and has no drive connection therewith. The arm 104 which, as before mentioned, is clamped between the two friction disks 102 on the shaft 14, as best shown in Figure 6, extends outwardly to the right, as viewed in Figures 2 and 3, its position being shown in dotted lines in the latter figure. This arm carries at its extremity a pin 103, best shown in Figure 7, the body of which is formed of an insulating material and the enlarged head 114 being of a conducting material. As best shown in Figure 7, the angled bracket 108 carries at one end and above the arm 104 a strip of insulating material 120 to which is secured the U-shaped strap 118 between the two vertical legs of which the contact 114 and the end of the arm 104 oscillate. Also carried on the upper leg and on the inner surface thereof of the strap 118 is a contact 116 which combines with the conducting point 114 of the pin 103 to provide a suitable switch. Since this bracket 108 is freely pivoted on the end of the rod 14, this U-shaped strap assumes any position to which it is forced by movement of the arm 104 and since the apparatus usually assumes a vertical position, as shown in Figure 2, the upper leg of the U-shaped strap 118 is normally forced against the contact 104.

Also associated with the strap 118 is a pivoted ratchet arm 132 which is supported so that the teeth 134 ride in a slot 136 in the upper arm of 75

the U-shaped strap 118. This ratchet means is so pivoted that the majority of its weight causes it to fall toward the rod 14 so that as the arm 104 causes the strap 118 to move upward, as viewed in Figure 2, its upper leg will ratchet against the ratchet means 134 and prevent the strap 118 from descending in case the arm 104 changes its direction of rotation under certain circumstances. The lower inside edge of the ratchet means is 5 tapered, as shown at 115 in Figure 3, so that as the arm 104 descends the insulating portion 103 of the pin will be forced thereagainst and push the ratchet means away from the strap 118 and allow the same to fall again by gravity to its position as shown in Figure 2 which in this instance is the "on" position of the mercury switch. There is also carried on the outer lower face of the lower leg of the strap 118 a contact 122 which is adapted to cooperate with a stationary contact 10 124 supported on the base.

Figures 3a and 3b show different relative positions of the parts during a cycle of operation. In Figure 3a the stack is cooling down and the arm 104 is rotating clockwise, the ratchet teeth 134 15 maintaining the bracket 118 in the upper position. At the instant shown in this view the insulating portion 103 contacts the tapered portion 115 of the ratchet arm 132 and any further movement will push the ratchet arm to the right 20 about its pivot and allow bracket 118 to fall which will allow contacts 122-124 to make.

In Figure 3b is shown a position of the arm 104 as the burner begins to heat from cold position and as it progresses up the sloping side 115 25 it allows the ratchet arm 132 to move to the left so that when 103 contacts the upper leg of bracket 118 and completes switch 114-116 the ratchet may engage the notch in bracket 118 and ratchet over the teeth 134 to prevent any return of the 30 bracket 118 and the notch 40 unless it is safe to do so.

It is therefore evident that in this portion of the construction there are provided three separate switches: (1) the mercury switch supported 35 on the outer end of the arm which is adapted to control the ignition circuit of the oil burner, (2) contacts 122 and 124 which are closed when the apparatus is in its closed or inoperative position, and, (3) contacts 114 and 116 which are 40 normally open when the device is in its inoperative or lowermost position, as shown in Figure 3, and closed in the heated or full line position shown therein. As the device rotates in a clockwise direction when bimetallic element 26 is 45 cooling, as shown in Figure 3, the ratchet will prevent the return of the bracket 108 unless the device 103 operates to push the ratchet out of 50 engaged position.

A conventional relay 42 is provided, said relay 55 being composed of a core 137 and a coil with an attractive armature 140 which is pivoted about a point 142, said pivoted member carrying thereon a plurality of arms 144 each of which has mounted thereon a contact member 146 and 148 60 respectively, said contacts cooperating with the two stationary contacts 150 and 152 on the base panel.

There is also provided on the base panel a conventional fuse block 154 and fuse 156 for protective purposes. A cover 188 is applied over the control apparatus and fits down around panel 8 and is held in position by any desired bolting means. The cover has a depression 190 therein with an opening for the reset button 68 to project through for operation.

The operation of the device may be best explained with reference to Figure 8 which shows the connective circuit thereto. Current is supplied to the transformer 36 from suitable means 158 and the transformer thus provides a low voltage source for the main portion of the controlling circuit in which a room thermostat 160, located in the space to be heated, initially actuates the whole control. When its contacts are closed current is supplied to the motor relay 42 through 10 the following circuit: Transformer 36, line 162, thermostat 160, line 164, warp switch contacts 52 and 60, line 166, contacts 122 and 124 (located on the bracket and the frame adjacent the stack switch), line 168, warp switch coil 56, line 170, 15 relay coil 42 and line 172 back to the transformer 36. This energizes the relay 42 which attracts its armature 140 closing its two series of contacts 150-146 and 152-148. The closing of the contacts 150 and 146 closes the high voltage circuit through the motor and ignition as follows: Incoming line 158, line 174, contacts 150-146, line 176, line 178, oil burner motor 180, and line 182 back to the incoming line. Also connected in parallel with the motor is the ignition transformer 184 and the mercury switch 112 mounted upon the end of the rod 14. The ignition transformer of course supplies a high tension current to a spark gap 186 across which high tension sparks jump, said gap being located in proximity 20 to the oil or gas discharged into the furnace. 25

At the same time that the contacts 150 and 146 are closed, contacts 152 and 148 are closed which closes a portion of the holding circuit for the relay coil 42, the rest of the circuit being controlled by the amount of heat generated by the furnace and as the rod 14, controlled by the bimetallic coil 26, turns it will cause the lever arm 104 to rise until contact 114 closes with contact 116 which completes the holding circuit for the 30 motor. When this happens, as can best be seen from Figure 3, the additional torque is transmitted to the arm 4 and tends to rotate the whole bracket 108 around the extension of rod 14 as a pivot. This breaks the contacts 122 and 124 45 which cuts out the warp switch coil 56 and prevents the warp switch from operating and also causes the mercury in the mercury switch 112 to flow to one end of the tube opening said contacts and cutting off the ignition. As the bracket 108 50 rotates it travels over the ratchet teeth 134 which prevents the same from returning in case of any abnormal condition, such operation proceeding until the room thermostat has been satisfied which then opens its contacts and deenergizes the 55 relay to open the main circuit.

If now, for example, the oil or fluid does not ignite, contacts 122 and 124 will remain closed allowing the warp switch to heat past its limit and the bimetallic element will warp out into the 60 opening in the arm 50 allowing contacts 52 and 60 to open and the whole circuit to be deenergized. Supposing further that the burner is operating normally upon a call for heat and for some reason or other the flame is extinguished, 65 the arm 104 will begin to rotate in a clockwise direction, as shown in either Figure 3 or 8, which breaks the circuit between contacts 114 and 116 to deenergize the relay coil and stop the motor. However, when the lever has returned to dotted 70 line position shown in Figure 3, it cams over the surface of the ratchet member 132 forcing the same to the right, which disengages the bracket and the ratchet teeth and allows the bracket 108 to return to its initial starting position which 75

closes both the ignition switch and contacts 122 and 124 to recycle the mechanism. The period however between the time of breaking the circuit between contacts 116-114 and mating contacts 5 122-124 is sufficient to allow combustible gases to escape from the furnace avoiding the danger of explosion and causing the device to recycle. If also there is a current failure the holding contacts 148 and 152 will be opened and the device 10 10 cannot again be energized until contacts 122 and 124 are allowed to meet and close the original energized circuit for the relay which allows again a time delay and a purging time for the furnace.

15 We claim:

1. In a control mechanism for fluid fuel burners, a panel, a rod rotatably carried therein, an arm mounted on the rod, friction driving means between the arm and rod influencing the arm to 20 rotate with the rod but allowing relative motion between the two, a member freely pivoted on the rod adapted to engage the arm and switching means carried by the pivoted means whereby the arm may tilt the pivoted means to actuate the 25 switch.

2. In a control mechanism for fluid fuel burners, a panel, a rod rotatably mounted in the panel, a member freely rotatable on the rod, a mercury bulb switch carried by the member, an angled 30 member insulated from and carried by the first named member, said angled member having a notch on one edge, a pivoted toothed latch on the panel fitting in the notch, an arm mounted on the rod, friction connecting means between 35 the rod and the arm, a contact on the end of the arm, a contact mounted adjacent the angled member on the panel and spaced contacts on the angled member cooperating with the contact on the arm and on the panel whereby when the 40 arm is rotated by the rod the various contacts change to control the burner and the pivoted arm is tilted to actuate the mercury switch, the latch preventing the return of the pivoted arm.

3. In a control mechanism for fluid fuel burners, a panel, a rod rotatably mounted in the panel, a member freely rotatable on the rod, a mercury switch carried on the member, an arm carried by the rod, friction drive means between the rod and the arm allowing relative motion 45 therebetween, said arm engaging a part of the pivoted member, a toothed latch pivotally mounted on the panel also engaging an edge of the pivoted member and in the path of the arc of movement of the arm, whereby the arm carries the pivoted member with it in one direction but the latch prevents it from returning upon a reversal of rotation until the arm engages the latch to push it aside and disengage the teeth 50 from contact with the pivoted member.

60 4. In a control mechanism for fluid fuel burners, a panel, a rod rotatably mounted in the panel,

an arm frictionally mounted on the rod to normally rotate therewith but adapted to have relative motion thereto if necessary, a member freely pivoted on the rod located to engage the arm whereby the arm may cause the member to rotate 5 about the axis of the rod and switch contacts carried by the arm and member and adapted to close when the arm contacts the member.

5. In a control mechanism for fluid fuel burners, a panel, a rod rotatably mounted in the 10 panel, an arm frictionally mounted on the rod to normally rotate therewith but adapted to have relative motion thereto if necessary, a member freely pivoted on the rod located to engage the arm whereby the arm may cause the member to 15 rotate about the axis of the rod, switch contacts carried by the arm and member and adapted to close when the arm contacts the member, a stationary contact located on the panel in the path of the member and a second contact on the member 20 adapted to engage the stationary contact to provide additional switching.

6. In a control mechanism for fluid fuel burners, a panel, a rod rotatably mounted in the panel, an arm frictionally mounted on the rod to normally rotate therewith but adapted to have relative motion thereto if necessary, a member freely pivoted on the rod located to engage the arm whereby the arm may cause the member to rotate 25 about the axis of the rod, switch contacts carried by the arm and member and adapted to close when the arm contacts the member and a toothed lever pivoted on the panel in juxtaposition to the member to engage the edge thereof for ratcheting purposes, said lever having a tapered 30 edge within the range of movement of the arm so that the latter may force the lever away from the member and release the ratchet.

7. In a control mechanism for fluid fuel burners, a panel, a rod rotatably mounted in the 40 panel, an arm frictionally mounted on the rod to normally rotate therewith but adapted to have relative motion thereto if necessary, a member freely pivoted on the rod located to engage the arm whereby the arm may cause the member to 45 rotate about the axis of the rod, switch contacts carried by the arm and member and adapted to close when the arm contacts the member, a stationary contact located on the panel in the path of the member, a second contact on the member 50 adapted to engage the stationary contact to provide additional switching and a toothed lever pivoted on the panel in juxtaposition to the member to engage the edge thereof for ratcheting purposes, said lever having a tapered edge within 55 the range of movement of the arm so that the latter may force the lever away from the member and release the ratchet.

WILLIAM H. HUTCHINS. 60
